UNITED STATES PATENT OFFICE.

WILLIAM H. HART, JR., OF PHILADELPHIA, PENNSYLVANIA.

BICYCLE-SUPPORT.

SPECIFICATION forming part of Letters Patent No. 636,664, dated November 7, 1899.

Application filed December 19, 1898. Serial No. 699,678. (No model.)

To all whom it may concern:

Be it known that I, WILLIAM H. HART, Jr., a citizen of the United States, residing in the city and county of Philadelphia, State of Pennsylvania, have invented a new and useful Improvement in Bicycle-Supports, which improvement is fully set forth in the following specification and accompanying drawings.

My invention consists of a bicycle-support formed of legs which are connectible with the frame of a bicycle-pedal and means on said leg for engaging it with said frame when the leg is in the operative position of a support.

Figure 1 represents a perspective view of a bicycle-support embodying my invention in operative position. Fig. 2 represents a top or plan view of the same in folded position. Fig. 3 represents a partial front view and partial vertical section. Fig. 4 represents a perspective view of another form of my invention in operative position. Fig. 5 represents a perspective view of the support of Fig. 4 removed from the pedal.

Similar letters of reference indicate corresponding parts in the figures.

Referring to the drawings, A designates a bicycle-pedal whose frame B has in the front part C thereof the openings D, in which are mounted the outturned journals E of the legs F, the latter being provided with the foot G, whereby said legs when in operative position may be firmly supported on a sidewalk, road, floor, or elsewhere. On the legs are freely mounted the sleeves H, to which are attached the plate J, which is thus adapted to slide on said legs to and from either end thereof. On said plate J is the stud K, which projects therefrom in the direction of the length of the legs F, and in the ears L on the inner or rear end of the pedal-frame is the eye or opening M, which is so disposed that when the legs are in inoperative position it is adapted to receive said stud K for retaining the legs in said position.

The operation is as follows: When the support is in inoperative position, it is folded on the pedal, as in Fig. 2, the slide or plate J being near the ear L and the stud K occupying the eye M therein, thus locking the legs to the pedal-frame. When service of

the support is required, the plate is moved from said ear L, whereby the stud K recedes from the eye M, and the legs then drop and assume a comparatively vertical position, 55 slightly thrown out at the base. The plate J is now raised, whereby it engages with the front end part of the pedal-frame B, as shown in Fig. 1, thus retaining the legs in their operative position and preventing inturning or 60 folding of the same. When, however, the plate is lowered, the legs may be returned to their folded position on the pedal-frame and locked therewith, as has been hereinbefore stated.

The legs are resilient in their nature, whereby their journals may be readily sprung into and out of the openings D.

In Figs. 4 and 5 the slide or sliding plate J has the stud P thereon, the same being 70 adapted to enter an eye or opening Q in the front portion C of the pedal-frame, so as to lock the legs when in operative position. When service of the support is not required, it may be removed from the pedal-frame by 75 lowering the plate J, as in Fig. 5, and pressing the legs from each other, whereby the journals N thereof emerge from the eyes or openings D in the pedal-frame, when the support is disconnected from the pedal and may 80 be carried in a pocket or elsewhere, as desired.

Having thus described my invention, what I claim as new, and desire to secure by Letters Patent, is—

1. In a bicycle-support attachable to a pedal-frame, a leg, a sliding sleeve on said leg, a plate on said sleeve, and a stud carried by said plate, said leg having a journal adapted to be mounted on said frame, and said stud 90 being adapted to engage said frame.

2. A pedal-frame provided with openings, a leg mounted in one of said openings, a sliding sleeve freely fitted on said leg, a plate connected with said sleeve and a stud on said plate adapted to enter the other opening of said frame.

3. In a bicycle-support, a leg, a sliding plate mounted thereon and a stud on said plate, said plate being adapted to engage 100 with the outer end of a pedal-frame, when the support is in operative position, and said stud

being adapted to engage with the inner end of said frame when the support is in folded position.

4. A pair of resilient legs, a base connecting the bottoms thereof and journals on the upper ends thereof, a sliding plate fitted on said legs, a stud on said plate, and a pedal-

frame having openings to receive said journals and an opening to receive said stud.

WILLIAM H. HART, JR.
